UNITED STATES PATENT OFFICE.

MEYER WOLF, OF NEW YORK, N. Y.

CIGARETTE-CONTAINER.

1,154,589.

Specification of Letters Patent. Patented Sept. 21, 1915.

Application filed November 19, 1914. Serial No. 872,898.

To all whom it may concern:

Be it known that I, MEYER WOLF, a citizen of the United States, residing at New York city, county of New York, and State 5 of New York, have invented a new and useful Improvement in Cigarette-Containers, of which the following is a full, clear, and exact description, reference being had to the accompanying drawings, which form a part 10 of this specification.

The object of my invention is to provide a box for cigarettes which, when opened, will present the cigarettes in such position that they may be readily removed.

15 More specifically the object is to provide a construction which is so simple and cheap that the same may be embodied in the original pasteboard box in which the cigarettes are sold by the retailer to the consumer, 20 avoiding any occasion for carrying a permanent and expensive cigarette case.

A preferred embodiment of the invention is shown in the accompanying drawings, in which—

25 Figure 1 is a perspective view of a cigarette box embodying my invention, shown in open condition. Fig. 2 is a plan view of same and Fig. 3 is a section on line 3—3 of Fig. 2.

30 The box, composed of the body *a* and lid *b*, need not differ in construction from that of an ordinary cigarette box. The lid is hinged at one end to the box body. Instead of placing the cigarettes loosely in the 35 box, as usual, a special receptacle *c* is provided for the cigarettes, the same comprising an open-ended receiver of a height approximately equal to half the length of the box. Preferably the receiver *c* is reinforced 40 adjacent to its bottom. A partition *d* extends within the receiver *c* parallel to, and midway between, the sides of the receiver, thereby dividing the same into two compartments. The partition *d* is preferably 45 substantially longer than the receiver *c* and may be nearly the length of the box *a* *b*. The partition may be secured in fixed relation to the receiver *c* by any convenient means, as, for instance, by making it originally of larger dimensions than the box and notching the edges thereof to form flanges *e* which may be bent over and secured to the bottom and ends of the receiver.

50 The receiver *c* is placed in the body *a* of the box. It may be pivotally attached to the

hinged end of the box, as shown, or not, as desired. A short flexible connection *f*, which may be a piece of tape, is secured at opposite ends to the bottom of the box body *a* and to one side of the receiver *c*, and another similar flexible connection *g* connects the other side of the receiver *c* and the lid of the box. The cigarettes are slipped lengthwise into the receiver *c* on opposite sides of the partition *d*. The lid of the box 60 is then closed.

It will be readily understood that in opening the box, the lid *b* will swing on its hinge until its further movement is restrained by the connections *f*, *g*. This movement causes 70 the receiver *c* to occupy a position angular to both the box body *a* and lid *b* and midway between both, thus bringing the cigarettes into an exposed position permitting their 75 ready removal.

It will be obvious that the construction is such that the invention may be applied to any ordinary cigarette box without modifying the construction of the box or increasing its size. It will also be observed that the 80 construction is so simple and inexpensive that the manufacturer can afford to apply it to his regular cigarette boxes without increasing the price to retailer or consumer.

Having now fully described my invention, 85 what I claim and desire to protect by Letters Patent is:

1. A cigarette container comprising a box body, a lid hinged thereto, a cigarette receiver of substantially less length than the box and placed therein with its closed end adjacent to the hinged end of the box, means connecting the receiver with the box lid and box body and limiting the outward movement of the body and lid when the same 95 have opened into an angular relationship, and a partition within the receiver midway between and parallel to the sides thereof and of a length substantially greater than that of the receiver and approximating that 100 of the body and lid and extending from the bottom of the receiver to a point substantially beyond the open end thereof and affording a support for two parallel rows of cigarettes.

2. A cigarette container comprising a box body, a lid hinged thereto, a cigarette receiver of substantially less length than the box and placed therein with its closed end adjacent to the hinged end of the box, means 110

connecting the receiver with the box lid and box body and limiting the outward movement of the body and lid when the same have opened into an annular relationship, 5 and a partition within the receiver midway between and parallel to the sides thereof, the edges of the partition being notched at intervals to form two sets of flanges which are bent respectively in opposite directions

and secured to the adjacent inside walls of 10 the receiver.

In testimony of which invention, I have hereunto-set my hand, at Philadelphia, on this 9th day of November, 1914.

MEYER WOLF.
